CARL MÜLLER AND JOHN DEACON, OF NEW YORK, N. Y.

Design No. 3,040, dated May 12, 1868.

DESIGN FOR A FIGURE.

The Schedule referred to in these Letters Patent and making part of the same.

TO ALL WHOM IT MAY CONCERN:

Be it known that we, CARL MÜLLER and JOHN DEACON, of the city, county, and State of New York, have invented a new and ornamental Design for a Figure; and we do hereby declare that the following is a full, clear, and exact description thereof, which will enable those skilled in the art to make and use the same, reference being had to the accompanying drawing, forming a part of this specification, in which the figure is represented by a perspective view.

This invention relates to a design for a figure, said figure being a base-ball pitcher in the act of pitching a ball, holding the same in his right hand. The pitcher is bent forward, resting his left hand on his knee, which is also bent. His shirt-front is thrown open, and his sleeve on his right arm is rolled up. On his waist he wears a belt, his pantaloons being tied around his ankle, and wearing base-ball shoes on his feet.

What we claim as new, and desire to secure by Letters Patent, for the term of three and a half years, is—
The design for a figure, as herein shown and described.

Signed, this 23d day of March, 1868.

CARL MÜLLER,
JNO. DEACON.
